PERMANENT WAVER

John Cirillo, New York, N. Y.

Application April 21, 1941, Serial No. 389,637

16 Claims. (Cl. 132—33)

This invention relates to hair curlers, and particularly, a hair curler with which the user may impart a permanent wave to her own hair.

An object of the invention is to provide apparatus with which the user may give herself a Croquignole type wave wherein, after a lock of hair is wound tightly around a mandrel, heat is applied by a heater surrounding the tightly wound hair.

Another object of the invention is to provide a permanent wave apparatus with which, after the hair has been tightly wound on a mandrel and heated by a surrounding heater, the heater may be removed and the curl left to cool and set with the hair-retaining portion of the mandrel inside the curl. It is further proposed to provide a special mandrel assembly having a hair-retaining portion easily separable from the handle portion so as to avoid drooping or sagging of the curl under the weight of the mandrel assembly, and, further, to avoid awkward obstructions on the user's head. Also, it is intended to provide a mandrel which cooperates with the heat applying element tightly to grip a curl during heating, but which mandrel later may be removed from the curl without uncurling, or altering the shape of the set curl whatsoever.

Another object is to provide a heat applying unit in which the heater element is isolated from the hair and scalp so as to avoid any burning of the user's scalp or hair, but wherein heat is thoroughly and uniformly applied to the curl.

And still further objects are to provide a permanent waver which may be handled by the "feel" thereof, or requiring at the most a simple, single mirror; a waver which may be held easily and without strain or fatigue on the user, which may be easily disassembled and assembled for cleaning; and which will not only impart permanent waves of pleasing appearance, but in the use of which the user will not appear at a disadvantage at any time. These and other advantages and objectives will be apparent from the following specification and drawings, in which:

Fig. 1 is a view showing the device in use during the first part of the procedure;

Fig. 2 shows the device in use during application of heat;

Fig. 3 shows several mandrel units still in place while the curls are cooling and setting;

Fig. 4 is an isometric view showing the assembly of parts;

Fig. 5 is a view, partially in vertical section, showing the complete device;

Fig. 6 is a transverse section along the line 6—6 of Fig. 5;

Fig. 7 is a transverse section along the line 7—7 of Fig. 5;

Fig. 8 is a view showing the mandrel assembly removed from the position shown in Fig. 5; and

Fig. 9 is a view showing an insulating cover for a portion of the heater.

Referring first to Figs. 4 to 8, inclusive, the reference numeral denotes a hollow cylindrical handle, preferably of material having good heat insulating properties such as found in any one of several well known plastics. Supported on the handle is a hollow receiver 4 which is open at both ends and has a longitudinal slot 6 in the side wall thereof and extending to the upper end. Preferably the receiver 4 is formed of aluminum or other metal having relatively good heat conducting properties. As shown best in Fig. 5, the receiver 4 has a tapering seat 8 flanged inwardly from the inner side wall below the end of the slot 6, seat 8 being substantially frustoconical in form. The lower end of receiver 4 is threaded at 10 to a hollow coupling 12, which in turn is threaded as indicated at 14 to a metal spool 16, the lower end of spool 16 being suitably affixed to the upper end of handle 2. Coupling 12 and spool 16 are also formed of metal, such as aluminum, having good heat conductive properties.

An electric resistance element 18 is wound on spool 16 and covered, as indicated by the reference numeral 20. At the lower end of spool 16 a guard piece 22 is flanged outwardly so as to notify the user when her hand approaches the resistance element and so as to hold the resistance element spaced from a table or the like when the device is at rest. At the lower end of the handle an insulated cord 24 is shown, cord 24 passing through handle 2 to resistance element 18 and having a plug (not shown) at the other end for connection with a standard electric outlet socket.

At the upper end of Figs. 4 and 5 a mandrel 26 is shown, the mandrel being split to provide spaced jaws 28, 28, the lower free ends of which terminate in tapered outer faces 30, 30. Removably attached to the upper end of mandrel 26 is a handle 32 having a socket 34 into which a plug element 36 at the upper end of mandrel 26 is releasably engageable by means of bayonet slot 38 in socket 34 and pin 40 on the periphery of plug element 36. The handle 30 is also provided with an abutment flange 42 which limits the downward movement of the mandrel assembly into the hollow receiver.

It is thus seen that the mandrel assembly including the mandrel proper and the handle, fits down into the upper open end of receiver 4. The mandrel assembly is held against displacement in the hollow receiver by the frictional engagement of the outer wall of socket 34 with the upper inner wall of the receiver. Comparing the condition of the mandrel as shown in Fig. 8 with that of Fig. 5, after the mandrel has been inserted into the receiver, it is seen that when the tapered free ends of jaws 30, 30 and 28, 28 are in place inside the receiver, the tapered free ends engage a tapering seat inside the receiver and, as the mandrel is pressed downwardly in the socket, tapering seat 8 forces the jaws together, thus to grip a curl of hair wound on the mandrel as will be later described.

In using the device it is intended that several mandrels 26 be available for connection with handle 32.

Referring particularly to Figs. 1 to 3, inclusive, the device operates as follows: Taking the mandrel assembly shown in Fig. 8, a strand of hair is isolated, inserted in the slot between jaws 28 of the mandrel and then wound as shown in Fig. 1. The receiver is then taken in one hand and inserted over the mandrel with the hair passing from the mandrel to the scalp through slot 6 in the receiver. After the receiver has been placed over the curl, the mandrel may be turned by rotation of the handle 32 in order to give the curl a final tightening. The receiver is then held in the position shown by Fig. 2 for a sufficient length of time, such as four, six or eight minutes, depending upon the hair texture and size of the curl, and then removed. Next, handle 32 is slightly rotated relative to mandrel 26 so as to free pin 40 from the bayonet slot, and then the handle is removed, thus leaving only the mandrel proper inside the curl. It is apparent that removal of the receiver 4 from around the curl also relaxes jaws 28 slightly from the curl so that the curl may be slightly adjusted, if necessary, after the receiver is removed. It is also apparent that the mandrel 26 will also retain some heat inside the curl to provide gradual cooling and final setting of the curl. Various hair waving and curl setting compositions may be used or may be applied to the hair, if desired, without danger of electrical shock to the user since the electrical resistance element 18 is completely isolated from the hair.

Reverting to Fig. 5 it will be seen that heat from resistance element 18 is conducted by the metal of coupling 12 and receiver 4 to the outside of the curl and additionally, to the inside of the curl and mandrel jaws 28 through metal to metal contact of the lower ends of the jaws with the tapering seat 8, and also to the inside of the curl through the hollow central portions of the spool 14, coupling 12 and receiver 4. Thus, even heat is applied throughout the entire cross-section of the curl. Heat loss through the slot 6 is deterred since, in operation, the slot is substantially closed by the hair itself, which has relatively good insulating properties. Fig. 9 illustrates a sleeve 44 of insulating material which may be placed over receiver 4 to deter heat loss and also to protect the user. If desired a thermostatic control element may be provided for limiting the amount of heat produced by the resistance element.

It is to be understood that the invention is not limited to the specific features shown and described, and that the full range of equivalents

and substitutions are to be attributed to the following claims.

I claim:

1. A hair waving apparatus, comprising a tubular receiving element having an open upper end and a slot through the side wall thereof extending from said upper end, heater means on said receiving element, handle means for supporting said receiving element adjacent the head of the user, a plurality of mandrels, each engageable into said receiving element, and a handle detachably engageable with one end of said mandrels whereby after strands of hair are wound on said mandrels, said mandrels may be inserted, successively, into said receiver for heating, with the strand of hair extending out through said slot to the user's scalp, removed from said receiver, and detached from said handle.

2. A hair waving apparatus, comprising a tubular receiving element having an open upper end and a slot through the side wall thereof extending from said upper end, heater means on said receiving element, handle means for supporting said receiving element adjacent the head of the user, a mandrel engageable into said receiving element through said open upper end, and abutment means on said mandrel engageable with said upper end for limiting the movement of said mandrel into said receiver.

3. A hair waving apparatus, comprising a tubular receiving element having an open upper end and a slot through the side wall thereof extending from said upper end, heater means on said receiving element, handle means for supporting said receiving element adjacent the head of the user, a mandrel engageable into said receiving element through said open upper end, and means on said mandrel engageable with the upper end of said receiver for holding said mandrel in placed position.

4. A hair waving apparatus as claimed in claim 3, the last-mentioned means comprising an element on said mandrel complementary with the inner side of the upper end of the receiver and frictionally engageable therewith.

5. A hair waving apparatus, comprising a tubular receiving element having an open upper end and a slot through the side wall thereof extending from said upper end, heater means on said receiving element, handle means for supporting said receiving element adjacent the head of the user, a mandrel engageable into said receiving element through said open upper end, said mandrel including a pair of jaws connected at one end, said jaws being spaced from one another at the lower end of said mandrel, and surface means on the inner wall of said receiver for engaging said jaws to force the jaws toward one another when said mandrel is inserted into said receiver.

6. A hair curling apparatus as claimed in claim 5, said surface means comprising a flange extending inwardly from the inner wall of the receiver.

7. A hair curling apparatus as claimed in claim 5, the free ends of said jaws being tapered.

8. A hair curling apparatus as claimed in claim 5, said surface means comprising an annular flange extending inwardly from the inner wall of the receiver and having an inverted frusto-conical upper surface, the free ends of said jaws being tapered.

9. A hair waving apparatus, comprising a tubular receiving element having an open upper end and a slot through the side wall extending from

said upper end for receiving a mandrel with hair wound thereon, a handle, means mounting said handle on the lower end of said receiver, and an electric-resistance element on the lower end of said receiving element.

10. A hair waving apparatus, comprising a tubular receiving element for surrounding a curl of hair and having open upper and lower ends and a slot through the side wall thereof extending from said upper end for allowing a strand of hair to extend from the curl to the exterior of the element, handle means on said receiving element for supporting the same adjacent the head of the user, an electric-resistance element, and means mounting said electric-resistance element at the lower end of said receiving element whereby the heat from said resistance element may pass directly to the interior of said receiving element to heat the curl therein.

11. A hair curling apparatus as claimed in claim 10, said receiving element and the means mounting said resistance element at the lower end thereof being formed of metal having relatively good heat-conducting properties whereby to transmit heat to the outer side of a curl in said receiving element.

12. A hair waving apparatus comprising a tubular receiving element for surrounding a curl of hair and having open upper and lower ends and a slot through the side wall thereof extending from said upper end for allowing a strand of hair to extend from the curl to the exterior of the element, an electric-resistance element mounted at the lower end of said receiving element, and a handle secured to the lower end of said receiving element, said handle and said receiving element forming an elongated, rod-like structure, said receiving element being formed of metal having relatively good heat-conducting properties, said handle being formed of heat-insulating material.

13. In a hair waving apparatus as claimed in claim 12, a sleeve formed of heat-insulating material surrounding said receiving element for shielding the user from heat radiating from said receiving element and for conserving heat in said receiving element.

14. In a hair waving apparatus as claimed in claim 12, an elongated mandrel engageable into said receiving element through the upper open end thereof, the upper end of said mandrel having an elongated handle of heat insulating material, said mandrel being formed of metal having relatively good heat conducting properties, said receiving element including a flange extending inwardly from the inner wall thereof to engage the lower end of said mandrel whereby to transmit heat thereto.

15. In a hair curling apparatus, an elongated receiving element comprised of a rigid piece of metal having an open upper end and a slot through the side wall thereof extending for part of the length of said receiving element from said upper end, an inwardly directed, annular flange on the inner wall of said piece, below the lower end of said slot, said flange having an upper surface inclined downwardly from the inner wall of the piece to a central opening, the lower end of said piece having internal threads thereon, a hollow coupling piece having a central portion, the outer wall of which is similar in end view to the outer wall of said receiving element, and upper and lower exteriorly threaded tubular elements extending above and below, respectively, said central portion, the upper threaded element being threadedly engaged with the threads in the lower end of said piece, an interiorly threaded thimble threadedly engaging the threads on the lower tubular element of said coupling piece, an electric-resistance element surrounding said thimble, a hollow cylindrical handle having an exteriorly threaded upper end threadedly engaged in said thimble, and an electric cord connected, at one end, to said electric-resistance element and extending through said hollow handle for connection with an electric outlet.
- 20 16. In combination with hair curling apparatus as claimed in claim 16, a mandrel assembly comprising a handle having an outwardly directed flange adjacent the lower end thereof and a hollow cylindrical element extending below said flange, said hollow cylindrical element having a bayonet slot therein, an elongated, rod-like element forming the mandrel proper and having an elongated slot extending upwardly from the lower end thereof to form elongated, spaced jaws, the top end of said rod-like element being substantially complementary with the interior of said hollow cylindrical element at the lower end of said handle and having a pin thereon engaging in said bayonet slot, the outer wall of the cylindrical element at the lower end of said handle being complementary with the inner wall of the upper end of said piece, the flange on said handle engaging the upper end of said piece, the length of said mandrel assembly, from said flange to the free ends of said jaws being substantially equal to the distance from the upper end of said piece to the lower end of the inclined upper surface of the inwardly directed flange in said piece.
